(57) **CLAIM**

The ornamental design for a swing hammer for particulate size reduction system, as shown and described in the attached specification.

DESCRIPTION

FIG. 1 is a perspective view of a swing hammer for a particulate size reduction system.

FIG. 2 is a plan view of a the swing hammer of FIG. 1.

FIG. 3 is a side elevation view of the swing hammer of FIG. 1.

FIG. 4 is a side elevation view of the swing hammer of FIG. 1, showing the side opposite that shown in FIG. 3.

FIG. 5 is an end elevation view of the swing hammer of FIG. 1, as viewed from the right as oriented in FIG. 2.

FIG. 6 is an end elevation view of the swing hammer of FIG. 1, showing the end opposite that shown in FIG. 5.

FIG. 7 is a perspective view of another representative embodiment of a swing hammer for a particulate size reduction system according to a second representative embodiment of the present invention.

FIG. 8 is a plan view of the swing hammer of FIG. 7.

FIG. 9 is a side elevation view of the swing hammer of FIG. 7.

FIG. 10 is a side elevation view of the swing hammer of FIG. 7, showing the side opposite that shown in FIG. 9.

FIG. 11 is an end elevation view of the swing hammer of FIG. 7, as viewed from the right as oriented in FIG. 8; and, FIG. 12 is an end elevation view of the swing hammer of FIG. 7, showing the end opposite that shown in FIG. 11.

The broken lines in the drawings depict unclaimed environmental subject matter.
